UNITED STATES PATENT OFFICE.

HAROLD ROWNTREE, OF CHICAGO, ILLINOIS, ASSIGNOR, BY MESNE ASSIGNMENTS, TO NATIONAL PNEUMATIC COMPANY, A CORPORATION OF WEST VIRGINIA.

DOOR-OPERATING MECHANISM.

1,002,180.

Specification of Letters Patent. Patented Aug. 29, 1911.

Application filed September 21, 1907. Serial No. 393,911.

To all whom it may concern:

Be it known that I, HAROLD ROWNTREE, a citizen of the United States, residing at Chicago, county of Cook, State of Illinois, have 5 made a certain new and useful Invention in Door-Operating Mechanism, of which the following is a specification.

This invention relates to door operating mechanism.

10 The object of the invention is to provide a door operating mechanism which is simple in construction and efficient in operation.

A further object of the invention is to provide means for operating doors, wherein 15 the movements of the door follow the movements of a control device or lever, the position of the door corresponding with the position of the control lever.

20 A further object of the invention is to provide a door operating motor and a controller therefor, said controller adapted to be operated by a control lever or other device to start the motor, thereby initiating the movement of the door, and means operated by 25 the movement of the door for operating the motor controller, whereby when the door reaches a position corresponding to the position to which the control lever has been moved, said door will be automatically arrested.

30 Other objects of the invention will appear more fully hereinafter.

The invention consists substantially in the construction, combination, location and relative arrangement of parts, all as will be 35 more fully hereinafter set forth, as shown in the accompanying drawing, and finally pointed out in the appended claims.

Referring to the accompanying drawing, 40 and to the various views and reference signs appearing thereon, Figure 1 is a view in elevation showing a door operating mechanism embodying the principles of my invention. Fig. 2 is a view, somewhat dia- 45 grammatic, showing a motor control apparatus well adapted for use in connection with my invention, said apparatus, in this instance, being in the form of a pressure controlling valve, said valve being in wide 50 open position. Fig. 3, is a view similar to Fig. 2, showing the valve on its center position. Fig. 4 is a similar view showing the valve on cushion position.

The same part is designated by the same reference sign wherever it occurs throughout 55 the several views.

In the operation of elevator doors or other closures it is important and desirable to maintain efficient control of the door and of the movements thereof. It is also important 60 and desirable to efficiently cushion the movements of the door, whether such door is moved the full extent of its travel or not. It is among the special purposes of the present invention to provide means whereby 65 these objects and purposes are attained in a most simple and efficient manner, and in carrying out my invention I provide a control device for the door operating motor and connections for operating the control 70 device manually to inaugurate the movements of the door and I also provide connections operated by the movements of the door for automatically operating the motor control device so as to arrest the movement 75 of the door when the latter attains a position corresponding to the position to which the controller was manually operated. I also propose to employ in connection with 80 my invention a control device of such construction and arrangement as to effect automatically a cushioning of the door as it approaches the limit of its movement as determined by the position to which the control device has been manually operated. 85

The objects and purposes above outlined may be carried out in a wide variety of specifically different constructions and arrangements of apparatus. While, therefore, I have shown and will now describe one construction and arrangement which I have found well adapted for the purposes, and the best form in which I at present contemplate carrying my invention into practical effect and operation my invention is by no 90 means to be limited or restricted to the particular construction shown and to be described.

In the drawing reference sign 5, designates a suitable operating motor, in this instance a motor cylinder, adapted to receive a motive fluid, such, for instance, as compressed air. A control apparatus, in this instance a valve device 6, controls the motor, that is, in the particular construction 105 shown, controls the supply and exhaust of

the motive power to and from each end of the cylinder. A cross head or other moving part 7, is operated by the motor, and the movements of this cross head or member 7, effect the operation of the door. Any suitable construction and arrangement of door operating mechanism may be employed. I have shown a simple and efficient construction wherein a rack 8, is connected 5 to move with the crosshead 7, and meshes with and rotatively moves a segment gear 9, to which is connected an operating arm 10, having a sliding or other suitable connection as at 11 with a door 12. It is to be 10 understood, however, that my invention 15 contemplates and includes any other suitable or convenient construction or arrangement of door operating devices, and therefore I am not to be limited or restricted in this 20 regard.

Pivottally connected at one end to the cross-head or movable member 7, is a lever 13, having connection, at a point adjacent its other end, through a link, rod or other 25 suitable connecting device 14, with the motor control device 6, in this instance, with an arm 15, attached to the motor control valve, whereby, when said lever 13, is rocked, the motor control device is operated. 30

Reference numeral 16, designates a handle, lever or other manual controlling device, connected in any convenient way as through connections 17, or otherwise, to the end of lever 13 adjacent the point of connection of 35 link 14, to said lever, whereby by manipulating the control handle or lever 16, the motor control device 6 is operated.

I will now describe the operation of the apparatus so far described.

40 Suppose the parts are in the position shown in full lines and the door is in closed position. Now suppose the device 16 is moved toward the right from such position. Thereupon, through the connections 17, the lever 13, is rocked to the left from the position thereof, shown, said lever rocking about its point of pivotal connection to the cross-head 7, as a fulcrum. The rocking movement of this lever 13, effects a corresponding movement of the motor controller 6 thereby starting up the motor and hence operating to move the cross-head toward the right and, through its connections with the door 12, inaugurating a movement of such 45 door. The movement of the cross-head 7, however carries the fulcrum of the lever 13, as above noted, with it, that is, through the resulting movement of the cross-head toward the right, the lever 13 is again 50 rocked, this time toward the right, its point of pivotal connection to the part 17, serving as a fulcrum, and hence the motor controller 6 is again operated, this time automatically 55 through the movement of the door operating mechanism and in a direction opposite

to that in which it was operated by the manual device 16. In other words, when the manual device operates the motor control valve from its cut-off or central position as shown in Fig. 3 to a wide open position, as shown in Fig. 2, thereby inaugurating the movement of the motor and hence, also, of the door operating mechanism, the automatic operation of the valve in the opposite direction by the movement 70 imparted by the motor, as before explained, is such as to return or restore the valve to center or cut-off position, thereby arresting the movement of the door. So too, if the manual device is moved in either direction, 75 or to any particular extent, it effects a movement of the motor control device in corresponding direction and to corresponding extent, thereby inaugurating an operation of the motor and of the door, and thereupon the motor or door operating means will cause an automatic movement of the controller in a direction opposite to that in which it was operated manually, and to a corresponding extent, thereby causing an 80 arrest of the movement of the door in a position corresponding exactly with the position to which the manual device or controller 16, had been operated. Consequently the movements of the door follow 85 the movement of the control lever 16, not only in direction but also in extent, the movement of the lever causing an inauguration of the movement of the door, and such movement operating means for causing an 90 automatic arrest of the door in position corresponding to that to which the control lever has been moved.

In Figs. 2, 3 and 4, I have indicated an arrangement of motor control valve which 95 I have found efficient for use in connection with my invention but which I do not claim, *per se*, herein, since such valve is not, in the specific construction thereof, of my invention, and hence is claimed herein only in 100 combination with other elements. In these views of the drawing 18 designates the pressure supply port, 19, 20, exhaust ports, and 21, 22, the ports for supplying the pressure medium to the respective ends of 105 the motor cylinder. The valve 23, controls these ports. This valve is formed with a passage 24, in the operating face thereof which, however, is not of sufficient distance 110 to span the space between the ports 21, 22. This passage is formed with enlarged chambers 25, 26, at the ends thereof said enlarged chambers being connected by a narrowed portion of the passage as shown. Preferably 115 a plurality of ports are employed. Two of such ports are shown, the one 19, being of large area, and the other 20, of small or restricted area. These ports are so relatively 120 arranged that all of them are uncovered when an enlarged chamber 25, 26, of the 125 130

valve passage 24, is brought thereover, that is, when the valve is shifted or moved to either limit of its stroke or movement, one of such limits being shown in Fig. 2. In 5 this position the supply port is opened to one end or the other of the cylinder while the opposite end of the cylinder is opened freely to exhaust through all the exhaust ports 19, 20. This is the wide open position 10 of the valve. Now if the valve is shifted sufficiently far to cause the larger exhaust port 19, to be closed, then the exhaust can continue only through the port 20 of limited or restricted area, see Fig. 4, thereby causing 15 a cushioning or slowing down of the mechanism operated by the motor until the motor, and hence, also, the mechanism operated thereby is finally arrested by the movement of the valve into centered or cut-off position, 20 see Fig. 3. It will be observed that the exhaust port 20, of limited or restricted area is always in communication with the valve passage 24, while the exhaust port of large area is opened only when the valve is actuated to 25 one or the other limits of its movement.

Now, referring to the mechanism above described for operating the motor controller, first manually, and then automatically in the opposite direction by the motor or other 30 devices set in motion by manual operation of the controller, it will be seen that when the motor controller is moved manually into wide open position in either direction from its closed or centered position, for instance, 35 from the position shown in Fig. 3 to the position shown in Fig. 2, the motor starts up, thereby operating the door moving means and in a direction as determined by the direction in which the controller has 40 been operated. Thereupon the operation of the door moving means effects a movement of the motor controlling valve in the opposite direction, or into the position shown in Fig. 4, thereby first cutting off the large exhaust port 19, which reduces the speed of 45 the door moving means, and then cuts off the port 21, thereby centering the valve see Fig. 3, and arresting the movement of the door, bringing the same to rest easily and 50 without slam. It will also be observed that this operation takes place whenever the valve is moved from centered position so as to open either port 21 or 22 to the supply of 55 pressure medium, and the extent of movement of the valve, and hence of the door, will be dependent upon the extent to which the manual device 16 is moved.

My invention is well adapted to the operation of doors, gates, or other closures or 60 obstructions, and by the use of the term door I desire to include any form of such device to be operated. It will also be noted that my invention is not limited to the operation of sliding doors but is equally well adapted for 65 use with pivoted hinged or other form of

movable door. It is also to be noted that my invention is not limited with respect to the construction of motor, control mechanism therefor or door operating means as these may vary widely in the specific details of 70 construction and arrangement thereof. But

Having now set forth the object and nature of my invention and a construction embodying the principles thereof, and having described such construction, its purpose, 75 function and mode of operation, what I claim as new and useful and of my own invention, and desire to secure by Letters Patent, is:

1. In a door operating mechanism, a 80 motor, a valve chamber having ports respectively communicating with a source of pressure supply and with opposite sides of the motor, and also having an exhaust opening, a valve for controlling said ports, said 85 valve having a recess in the operating face thereof to constantly register with a portion of the exhaust opening, said recess being of such length as to embrace the full exhaust opening and a motor port when shifted from 90 centered position, said valve when in centered position operating to cut off pressure supply to the motor, manually operated devices for shifting the valve in either direction from centered position to uncover all 95 the exhaust opening and to open one side or the other of the motor to pressure supply to start the motor, means operated by the motor to return the valve toward centered position to arrest the motor in position corresponding 100 to the position to which the manual devices are operated, said valve having means to reduce the area of exhaust opening in advance of reducing the pressure supply area, as the motor approaches the limit of its movement 105 as determined by the position of the manual devices, and door operating devices actuated by the motor.

2. In a door operating mechanism, a 110 pressure operated motor, door moving devices actuated thereby, a control handle, means operated by said handle for controlling the supply and exhaust of pressure medium to and from the motor, means to cause the motor to follow, in direction and extent of operation, the movements of the control handle, and means for restricting the exhaust of operating medium from the motor, without affecting the supply thereto, as the motor approaches the final limit of 115 its operation to whatever extent it may be operated.

3. In a door operating mechanism, a 120 pressure operated motor, door moving devices actuated thereby, manually operated devices for controlling the initial movement of the motor, mechanism operated by the motor, when once put in operation, for automatically arresting the same in position corresponding to the position to which the 125 130

manual devices are operated, and means for restricting the exhaust of power medium from the motor, as it approaches the final limit of its action as determined by the 5 manual devices, without affecting the supply of power medium thereto.

4. In a door operating mechanism, a pressure operated motor, door moving devices actuated thereby, manually operated 10 devices for starting the motor, automatic means operated by the motor, when once started up, for arresting the motor in position as determined by the manually operated devices, said automatic means operating 15 to restrict the exhaust of operating medium from the motor, as it approaches the limit of its operation, without affecting the supply of operating medium to the motor.

5. In a door operating mechanism, a 20 pressure operated motor, door moving devices actuated thereby, a controller for controlling the supply and exhaust of operating medium to and from said motor, said controller, when in centered position operating 25 to cut off pressure supply without closing the exhaust, means for operating the controller to various positions from its centered position to supply full pressure to the motor on one side and to open the other side 30 to full exhaust to start the motor, and means operated by the motor for actuating the controller in reverse direction to restrict the exhaust of pressure medium from the motor without affecting the pressure supply, as the 35 motor approaches the limit of its action, as determined by the position to which the controller is operated to start the motor.

6. In a door operating mechanism, a 40 pressure operated motor, a valve, pressure supply and exhaust connections to and from the motor arranged to be controlled by the valve, said valve when in centered position operating to close the pressure supply connection to the motor but not the exhaust 45 manually operated devices for moving the valve to various positions from its centered position, in each of which the motor is opened to full pressure supply on one side and to full exhaust on the other to start the 50 motor, means operated by the motor when once started up for reversely shifting the valve into cut off position to arrest the motor in position corresponding to that to which the manually operated devices have 55 been actuated, said valve, operating to restrict the exhaust opening without substan-

tially affecting the pressure supply, from whatever point the valve is operated toward centered position and door moving devices operated by the motor.

60

7. In a door operating mechanism, a pressure operated motor, a controller for controlling the supply and exhaust of operating medium to and from the motor, an operating handle for the controller adapted 65 to be set to various positions, devices operated by the motor and connected to the controller to move the same in reverse direction to that in which it is moved by said handle, and to corresponding extent, to cut 70 off the pressure medium from and to arrest the motor in position corresponding to the position to which the handle is operated, said controller operating to restrict the exhaust of pressure medium before the supply 75 pressure is restricted, as it approaches its cut off position, and door moving devices operated by the motor.

8. In a door operating mechanism, a pressure operated motor having a valve casting with pressure supply and exhaust connections to and from the motor, a valve for controlling the motor, said valve, when in centered position operating to close the pressure supply connections to the motor 85 but not the exhaust therefrom, a control handle for shifting the valve to various positions from its centered position, corresponding in extent to that to which the control handle is moved, said valve operating 90 when shifted from its centered position to any substantial extent to open full pressure supply to the motor, means operated by the motor for returning the valve to its centered position to arrest the motor in position corresponding to that to which the control 95 handle is shifted, the valve operating to restrict the exhaust from the cylinder before it commences to cut off the pressure supply, as it approaches its centered position from 100 whatever point it may be returned to centered position, and door moving devices actuated by the motor.

In testimony whereof I have hereunto set my hand in the presence of the subscribing 105 witnesses, on this 10th day of September A. D., 1907.

HAROLD ROWNTREE.
